BRIQUETTING PRESS

Robert James Piersol, Urbana, Ill.

Application April 17, 1937, Serial No. 137,462

6 Claims. (Cl. 25—64)

An object of my invention is to provide a press for briquetting material at high pressures.

More particularly it is an object of the invention to provide a press particularly adapted for the formation of a briquetted ribbon formed of bituminous coal without the aid of an artificial binder, compressed at pressures up to seventy thousand pounds per square inch, the press being adaptable for practicing the method of briquetting coal which is disclosed in my United States Letters Patent No. 2,021,020. The method disclosed in said patent consists of a process for briquetting either raw bituminous coal or partially volatilized bituminous coal without the aid of added binders by an impact of a magnitude up to thirty thousand foot-pounds per pound of coal at temperatures up to four hundred degrees centigrade.

I have found by experiment that these energies of impact are equivalent to briquetting pressures up to seventy thousand pounds per square inch and that without the use of added binders a stronger and denser briquette is made from bituminous coals by an impact blow from a falling weight or an impact blow delivered by a rapidly moving plunger than that obtained by the slow application of a steady pressure.

Accordingly it is an important object of my present invention to provide a briquetting press capable of delivering pressures up to seventy thousand pounds per square inch at a rapid rate comparable to impaction as contrasted to the time of compression in the usual high pressure hydraulic or mechanical presses, the press being adaptable for the briquetting of coal without the use of added binders, the cost of which forms the chief item of expense in briquetting coal.

Another object is to provide a press which will accomplish the desired results with parts which rotate, thus resulting in the elimination of any reciprocating parts and the attendant periodicity of motion in operation.

A further object is to provide a press in which the area of the plunger and die surfaces subject to wear are a minimum for the quantity of briquettes produced and their movement is such that the press can operate at an unusually high speed without appreciable wear on the plunger and die surfaces and thus it is possible to obtain a relatively high briquetting capacity for the press.

A further object is to construct the plunger and die members of a press so that during all stages of impaction the coal is confined so that the application of high pressure will result in the desired impaction of strong stable briquettes without ex-

trusion of the temporarily fluid coal between the plunger and die, the coacting surfaces of which are so formed that there is perfect alignment during all stages of impaction.

Another object is to provide a press so designed that it is fully automatic in character, thus eliminating the necessity of any manual operation.

More particularly it is my object to provide a press in which the die members are formed on a pair of rotary discs, the faces of which are arranged at a slight angle to each other, the die members being an annular trough and an annular plunger respectively, coacting with each other and the coacting surfaces thereof being formed on a radius from the intersection of the axes of rotation of the discs and thus actually being sections of two concentric spherical shells.

With these and other objects in view my invention consists in the construction, arrangement and combination of the various parts of my device, whereby the objects contemplated are attained, as hereinafter more fully set forth, pointed out in my claims and illustrated in the accompanying drawing, in which:

Figure 1 is a vertical sectional view through a briquetting press embodying my invention.

Figure 2 is a plan view of the same on a reduced scale.

Figure 3 is a sectional view on line 3—3 of Figure 2 enlarged approximately to the scale of Figure 1; and

Figure 4 is a diagrammatic vertical sectional view of a slightly modified construction.

On the accompanying drawing I have used the reference characters B to indicate a supporting base for my press and D for a lower disc and D' to indicate an upper disc. The discs D and D' carry the die members, one of which is indicated at 10 and the other at 12. The die members 10 and 12 are annular in character, the die member 10 having an annular trough 11 formed therein and the die member 12 having an annular plunger 13 projecting therefrom.

The discs D and D' are mounted on shafts 14 and 15 respectively. The shaft 14 is journaled in a bearing 16 of the base B. This bearing is preferably of roller or ball type (not shown). Similarly the shaft 15 is journaled in a sleeve 17. The sleeve 17 is vertically slidable in a hub 18 of a top plate T, which in conjunction with supporting posts 19 constitutes a frame for the press.

The axes of the shafts 14 and 15 are indicated at 14' and 15' respectively. These, it will be noted, intersect at a point marked X. The sides of the annular trough 11 and of the annular plunger 13

are formed on a radius from the point X, thus being sections of two concentric or parallel spherical shells, indicated by dash lines 20 and 21.

The discs D and D' are preferably backed by 5 annular rows of tapered roller bearings 22 and 23 seating against the backs of the discs and against a base seat 24 and a top ring 26. The top ring 26 is vertically slidable in an annular trough 27 of the top T and is backed by a plurality of coil springs 28. These tend to maintain 10 a predetermined pressure against the disc D' but permit the disc to move upwardly slightly for a governing purpose, which will hereinafter be described, when the pressure exceeds a certain predetermined pressure, downward movement of the 15 disc D' being limited by a head 29 on the shaft 15 and a shoulder 30 on the hub 18 supporting the sleeve 17.

The discs D and D' may be rotated by any 20 suitable mechanism. By way of example, I show a ring worm gear 31 on the disc D and a ring worm gear 32 on the disc D'. These mesh with a pair of worms 33 which are driven by sprockets 34. The sprockets 34 are operatively connected 25 by a chain 35 and a sprocket 36 to an electric motor 37.

The arrangement of the discs D and D' at an angle as illustrated and in the position relative to each other illustrated causes a variable degree of coaction between the right hand sides of the discs as shown in Figure 1 with the annular plunger 13 partially entering the annular trough 11.

At the left sides of the discs the plunger and 35 trough are relatively spread apart. This is perhaps better shown in Figure 3, wherein a bracket 38 indicates the section of the plunger and trough which coact with each other while the point of greatest spread between the trough and plunger 40 is indicated at 39.

Located at the left side of the frame for the press, I provide an extracting trough 40 for completed briquettes and an inlet chute 41 is provided for the coal entering the press to be compressed. The coal may be supplied to the chute 41 from any suitable source in the form of granules of proper size.

The coal leaves the chute 41 as indicated at C in Figure 3 and as the discs D and D' rotate 50 synchronously in the direction of the arrows a it is troweled down by a leveling blade 42 to the desired level in the trough 11. The coal, where it is troweled down, is indicated at C'.

As the discs rotate the plunger 13 enters the 55 trough 11 at the point indicated at 43 in Figure 3 and the plunger engages the coal C' at a point indicated at 44.

Between this point and a releasing point, indicated at 45, the coal is rapidly compressed from 60 the thickness indicated at C' to a thickness indicated at C''. The compressed coal C'' travels with the disc D to the extracting trough 40 up which it is pushed by the rotation of the disc. This trough is pivotally mounted at 46 so that its intake end rides in the bottom of the trough 65 11 to effectively pick up the compressed coal C''.

At the top of the trough 40 rollers 47 are provided between which the briquetted ribbon of the compressed coal C'' is projected and a breaker 70 roller 48 is provided for breaking the ribbon into briquettes, indicated as C'''. The briquettes C''' may slide by gravity down a chute 49 to a suitable conveyor or place of deposit. For the purpose of scoring the briquetted ribbon C'' so that 75 it can be readily broken into briquettes C''',

I provide the annular plunger 13 with cross beads 50.

The leveling blade 42 is mounted on a rock shaft 51 on which is also mounted an arm 52. The arm 52 is adapted to be moved downwardly 5 for reducing the level of the coal at C' by a rod 53 and an arm 54. The arm 54 is mounted on a rock shaft 55 from which extends an arm 56 contacting with the upper end of the shaft 15.

Practical operation

10

As before mentioned, one of the essential features of the press is perfect alignment of the plunger and die throughout all stages of compression. This alignment is secured even though 15 the discs D and D' rotate relative to each other and are positioned at an angle relative to each other by having the outer and inner walls of the trough 11 and of the trough 11 and of the die 13 formed as parts of the two concentric shells 20 20 and 21. As a further aid to secure alignment, the shafts 14 and 15 may be extended as in Figure 4 and joined by a ball and socket joint 14''—15''.

There is clearance, of course, between the walls 25 11 and 13 of a few thousandths of an inch to permit free motion, but not enough to allow extrusion of the material C' as it is being briquetted. The trough 11 is filleted at both edges 30 20 and 21. As a further aid to secure alignment, the shafts 14 and 15 may be extended as in Figure 4 and joined by a ball and socket joint 14''—15''.

In usual commercial practice the plunger system will rotate at the same speed as the die system, due to the drag of the material being briquetted so that only the disc D need be driven. 35 Driving both discs, however, insures proper synchronization of the plunger system with the die system.

The material being fed to the die at C is leveled by the blade 42 to the desired thickness and compressed between the points 44 and 45 by the plunger entering the die or trough 11. The chute 41, if desired, may be vibrated to insure a more uniform rate of feeding. The traveling blade 42 may be set at a predetermined position if it is 40 not necessary, due to the nature of the material being briquetted, to frequently regulate the rate of feeding in response to variations in the maximum pressure exerted by the press on the material being briquetted. I have shown automatic 45 means for regulating the blade 42 consisting of the arms 54 and 56, the rod 53 and the arm 52. Whenever the briquetting pressure exceeds a predetermined pressure, as determined by the tension of the springs 28, the disc D' will float upwardly a slight distance and will move the blade 42 downwardly in proportion thereto, thus decreasing the thickness of the material at C' and thereby reducing the pressure exerted by the 50 press.

The briquetted ribbon C'' is removed from the trough 11 by the extracting trough 40 and as the ribbon strikes the roller 48 it is bent downwardly, thus breaking sections of the ribbon off at the 55 V-shaped notches 57 formed therein by the beads 50 of the plunger 13.

The desirable speed of rotation of the press depends to a large degree on its die diameter, the speed, of course being less for larger diameters. 70 For a commercial press having a forty-eight inch diameter, a desirable speed is fifty R. P. M. This corresponds to peripheral speed of six hundred twenty-eight feet per minute. If the briquetted ribbon is four inches wide and two inches thick, 75

the capacity of such a press is about fifty tons per hour.

In order to explain the actual operation of my press, I shall describe its operation for one specific use which is the briquetting of high volatile bituminous coals without added binders.

The coal to be briquetted is ground or crushed to a size of minus four mesh. This fine coal is heated to a temperature of about two hundred fifty degrees centigrade, in any suitable type of preheater, the period of preheating being about ten minutes.

The coal maintained at this stated temperature is fed directly into the press herein described. In order to form strong briquettes it is necessary that the plunger and die be maintained at this temperature. In starting briquetting operations, I have found that the most convenient method of heating the plunger and die to this temperature is to pass the heated material through the press. About ten minutes is required to raise the plunger and die to the desired temperature and thereafter the temperature remains approximately that of the incoming coal. The briquettes made during the warming up period are too soft for commercial use and may be returned to the crusher and re-used.

The correct rate of feed for each type of coal may be determined by trial runs with the press. The finished briquettes may be conveyed either to storage, freight cars or trucks. Even without cooling, the shape of the briquettes results in large pore space between briquettes when piled, thereby providing free circulation of air and thus eliminating the hazard of spontaneous combustion.

It is my intent not to limit the scope of this invention to the one particular design illustrated nor to limit the use of the press to the briquetting of coal. On the other hand the design of the press can be modified considerably and the press may be used for various types of molded materials requiring unusually high pressures at relatively high speeds for their formation without departing from the real spirit and purpose of my invention and it is my intention to cover by my claims any modified forms of structure or use of mechanical equivalents which may be reasonably included within their scope.

50 I claim as my invention:

1. A press of the character described including die and plunger members telescopically movable relative to each other, the sliding surfaces thereof being portions of two concentric spheres, means for feeding material to the space between said members as they move relative to each other and means for regulating the rate of feeding, said

means being responsive to the pressure of the plunger relative to the die whereby to decrease the rate of feed when the resultant maximum pressure on the briquette being formed exceeds a predetermined value.

5

2. A briquetting press including a die and a plunger telescopically movable relative to each other and having sliding surfaces which are portions of two concentric spheres, means for propelling said die and plunger telescopically relative to each other and also in another direction and means for extracting briquettes from said press comprising a blade extending thereinto on to which the briquettes are projected by movement of the press in said other direction.

10

3. A briquetting press of the character described including coacting die and plunger members which move toward and away from each other and also in another direction, projections on said plunger to score a briquetted ribbon formed in said press and means for automatically breaking the briquetted ribbon along the scoring thereof.

15

4. A device for compressing material comprising a pair of rotatably mounted discs arranged at an angle relative to each other, an annular trough formed in one of said discs, an annular projection on the other disc having a portion thereof entering said annular trough, the coacting sides of said trough and projection being formed on a radius from the intersection of the axes of rotation of said discs.

20

5. A rotary briquetting press comprising two circular disks, a die comprising an annular groove in one of said disks, a plunger comprising an annular flange on the other of said disks and co-operating with said die, the cooperating surfaces of said die and plunger being portions of concentric spherical shells, said disks being rotatably mounted and the axes of rotation thereof being inclined at an angle with relation to each other.

25

6. A rotary briquetting press comprising two circular disks, arranged one above the other, an annular groove in the lower disk constituting a die, an annular flange on the upper disk constituting a plunger, said disks being rotatably mounted, the axes of rotation thereof being inclined relative to each other, said flange being received in said groove throughout a portion of the circumference thereof and the coacting surfaces of said flange and said groove being formed as portions of concentric spherical shells, the axes of rotation of said disks intersecting at a point between the disks above the top of said groove and below the bottom of said flange.
